UNITED STATES PATENT OFFICE

EARL E. MAXWELL, OF BOSTON, MASSACHUSETTS

DESIGN FOR AN IGNITION METER

Application filed December 4, 1930. Serial No. 37,882. Term of patent 14 years.

To all whom it may concern:

Be it known that I, EARL E. MAXWELL, a citizen of the United States, and a resident of Boston, in the county of Suffolk and State of Massachusetts, have invented a new, original, and ornamental Design for an Ignition Meter, of which the following is a specification, reference being had to the accompanying drawing, forming part thereof.

Referring to the drawing:

Fig. 1 is a front elevation of an ignition meter showing my new design; and
Fig. 2 is a top plan view of said meter.

I claim:

The ornamental design for an ignition meter, substantially as shown.

In witness whereof, I hereunto subscribe my name this fifteenth day of November, 1930.

EARL E. MAXWELL.
